UNITED STATES PATENT OFFICE.

WILLIAM D. DENTON AND ROBERT W. DENTON, OF WELLESLEY, MASSACHUSETTS.

ART OF SIMULATING RARE, PRECIOUS, AND OTHER STONES.

No. 889,845.

Specification of Letters Patent.

Patented June 2, 1908.

Application filed February 26, 1906. Serial No. 303,112.

To all whom it may concern:

Be it known that we, WILLIAM D. DENTON and ROBERT W. DENTON, citizens of the United States, residing at Wellesley, in the 5 county of Norfolk and State of Massachusetts, have invented new and useful Improvements in the Art of Simulating Rare, Precious, and other Stones, of which the following is a specification.

10 The present invention relates to improvements in the fine arts and particularly in the art of decorative work, and it has for its object a utilization of regular geometrical sections of the wings of insects, particularly 15 sections taken from the beautifully colored wings of the butterfly and moth, the coloring and texture of many of which when used in accordance with our invention blend themselves most effectively to work in decorative 20 or fine arts.

We have discovered that by taking a section of the wing of a butterfly or moth of a definite, and preferably of a symmetrical, area, and mounting it in a suitable manner, 25 for example, in a brooch, locket, or other ornamental setting, the identity of the wing, as such, is destroyed, and a highly ornamental and jewel-like effect is produced.

Our discovery lends itself particularly to 30 the simulation of rare, precious or other stones, so that by practicing the invention as herein disclosed, jewelry, articles of personal adornment, toilet articles, bric-a-brac, ornaments, articles of vertu, and the like, 35 may be produced, in which jewels, valuable minerals, and geological specimens, may be closely imitated, while at the same time the articles thus ornamented and enriched can be produced at a nominal cost so far as the 40 simulated rare settings are concerned.

In practicing this improvement, advantage is taken of the fact that the wings of insects, of the butterfly and moth families, especially in some of the highly-colored and 45 brilliant groups, is closely imitative in coloring and textural appearance of rare, precious and other stones or minerals. For example, the "opal" butterfly has an upper wing surface which possesses all the depth, iridescence, and shifting colors of the opal. Another has the coloring of the agate, to 50 which coloring the wing texture or make-up, with its fine traceries of veins and membranes, lends an effective imitative effect.

Again, some of the other types carry upon 55 their wings well-defined and regularly formed spots, which, when displayed under certain conditions made possible by the practice of our invention, resembles the cat's eye. Others have the blue of the lapis-lazuli, the 60 gray of the pearl, and so on, through an almost endless line of resemblances.

It is obvious that the manner in which this 65 novel art of ornamentation or embellishment articles in which the decorative effects may be advantageously utilized are manifold. It will be observed, however, from the detailed description which follows hereinafter, that in whatever form or expression the improvement 70 in decorative art and jewel simulation which we have invented may appear, its practice entails certain requirements to give attractive decorative effects, and, where 75 simulative results are desired, to secure the full value of imitative effects, and accurate simulation of the natural products which it is desired to reproduce.

In order to effectively utilize the textural 80 structure, iridescence, and color properties of the butterfly wing in practicing our invention, it is indispensable that the identity of the wing, as such, be entirely eliminated or destroyed, so as to leave on the eye of the observer only the color and textural effect, to 85 the end that the jewel-like appearance may predominate, to the exclusion of other impressions; and for the obvious reason that when simulation of stones is aimed at, any indication of the nature of the material used in 90 practicing this art would detract from the realistic impression of solidity, depth, etc., necessary to successful imitation. This blotting out of the identity of the wing may, we 95 have discovered, be very effectually brought about by taking a wing, or a section of a wing, which section may, if desired, be cut to a regular outline, and exposing an unbroken area or portion thereof through an aperture or sight opening, preferably glazed, of such a 100 pattern as would lend itself to the decorative scheme if worked out with rare or precious stones, so as that the effect of a jewel or article of adornment having a regular setting of rare, precious or other stones is produced.

105 It will be obvious that the art may be practiced in a variety of different ways, but as illustrating some of the methods of putting
